INVENTOR
BY Victor J. Evans

ATTORNEY

WITNESS:

UNITED STATES PATENT OFFICE.

HERMAN F. HARDY, OF NEAR LA GRANGE, NORTH CAROLINA.

GRAPE ARBOR.

Application filed April 3, 1922. Serial No. 549,044.

To all whom it may concern:

Be it known that I, HERMAN F. HARDY, a citizen of the United States, residing near La Grange, in the county of Greene, and 5 State of North Carolina, have invented new and useful Improvements in Grape Arbors, of which the following is a specification.

My present invention has reference to an arbor for vines and which, when fully 10 covered by the vines may be employed as a summer house.

The primary object of the invention is to produce a support for vines in which the framework thereof is constructed of pipe 15 members and couplings therefor, neither the pipes nor the couplings, however, being threaded, but being temporarily connected in a simple, cheap and novel manner to permit of wires which form the main supports 20 for the vines being arranged over and secured to the said pipe members, and whereby an arbor, trellis or other support for vines may be erected by an unskilled person in an easy, expeditious as well as in a strong 25 and effective manner.

The foregoing, and other objects which will present themselves as the nature of the invention is better understood, may be accomplished by a construction, combination 30 and operative association of parts such as is disclosed by the drawings which accompany and which form part of this specification.

In the drawings:—
35 Figure 1 is a top plan view of the improvement.

Figure 2 is a side elevation with parts broken away and parts in section.

Figure 3 is a perspective view showing 40 the manner in which the pipe sections are temporarily secured on the couplings therefor.

Figure 4 is a perspective view of one of the foot members employed.

45 The main framework of my improvement is in the nature of metal pipes. As it is one of the primary objects of my invention to provide a means whereby the frame may be erected in an easy, expeditious manner, the 45 pipes constituting the frame do not have their ends threaded. Preferably all of the pipes which constitute the top of the frame are all of the same length and also the supporting pipes or standards are likewise of 50 an equal length so that a neat and artistic construction is presented. For distinction, 55

the standards or uprights are indicated by the numeral 1, the longitudinal pipes by the numeral 2 and the cross pipes by the numeral 3. The longitudinal and transverse 60 pipes 2 and 3 have their confronting ends received in sockets provided by cross couplings 4. These couplings have centrally arranged depending sockets 5 which freely receive therein the upper ends of the standards 65 1. The longitudinal and cross pipes 2 and 3, adjacent to their ends have small openings 6 therethrough, and in a like manner the standards 1 are provided with smaller openings 7 adjacent to their upper ends. I pass 70 7 through all of these openings a wire strand 8, and I connect the ends of the strand by twisting the same, as indicated by the numeral 9, and as clearly illustrated in Figure 3 of the drawings. In this manner, it will 75 be seen that the longitudinal, cross and uprights pipes are effectively connected without necessitating the threaded engagement between the pipes and the couplings therefor. The locking means, however, is only 80 temporary, as I twist around the outer pipe sections 2 and 3 of the frame transverse and longitudinally arranged wires 10 and 11 respectively. These wires provide a foraminous top for the frame, and, of course, if 85 desired, the wires may be twisted or coiled around the inner longitudinal and transverse pipe sections of the top of the frame.

To prevent the standards 1 sinking into the ground, I provide foot members which 90 include each a flat base 13 on which is centrally formed a projection 14 which is of a size to be snugly received in the lower ends of the said standards 1.

As previously inferred, the wires 8 are removed from the frame structure when the arbor or trellis wires 10 and 11 are arranged thereon, as the said wires 10 and 11 will effectively hold the pipe sections which constitute the top of the trellis or arbor together, and it is believed that the foregoing description, when taken in connection with the drawings will fully set forth the construction and advantages of the improvement to those skilled in the art to which such 105 inventions relate.

Having described the invention, I claim:—

1. In a device for the purpose set forth, comprising a frame including tubular standards which constitute the uprights of a frame 110 and tubular longitudinal and transverse members which constitute the top of the

frame, T-couplings having central sockets which latter receive therein the upper ends of the standards and which couplings have their remaining sockets receiving therein the confronting ends of the longitudinal and transverse tubular members, removable means securing the tubular members in the sockets of the couplings, and spaced longitudinal and cross wires connected to the tubular top members of the frame.

2. In a device for the purpose set forth, tubular members and couplings constituting a frame, each of said tubular members being approximately of an equal length, cross couplings freely receiving the confronting ends of the top members of the frame therein, each of said cross couplings having a depending socket to receive the vertical members of the frame therein, wire strands removably connecting the top and vertical members of the frame with the couplings, longitudinal and cross wires secured to the

top of the frame, and foot members for the standards each including a base to rest on the ground and a projection to be received in the lower ends of the standards.

3. In a device for the purpose set forth, a frame made up of tubular members including vertical standards, removable foot members therefor, cross couplings having sockets receiving the upper ends of the standards therein and longitudinal and transverse tubular members received in the horizontal branches of the cross sockets, all of said members, at points adjacent to their connection with the couplings having openings therethrough and said members at their jointure with the couplings having a single strand of wire passing through said couplings and the ends of the said wire being twisted to connect the same.

In testimony whereof I affix my signature.

HERMAN F. HARDY.
